PROGRESSIVE ILLUMINATING MEANS

Leonard E. Ludvigsen, Los Angeles, Calif., assignor to Mega Corporation, Los Angeles, Calif., a corporation of California

Application June 23, 1947, Serial No. 756,440

18 Claims. (Cl. 315—315)

1

The present invention relates to improvements in progressive illuminating means.

More particularly, the present invention relates to installations employing gaseous discharge tubes which may be illuminated when supplied with electric current. One or more of such tubes may be employed in the practice of the present invention for providing illumination progressing from point to point and repeating itself cyclically.

An object of the present invention is to provide improved progressive illuminating means which employs mechanism that is sturdy and not likely to get out of order.

A further object is to provide progressive illuminating means employing hot cathode tubes which illuminating means are certain in operation and avoid the necessity for excessively high voltages.

A further object is to provide progressive illuminating means involving relatively simple magnetic structures for controlling its functions.

A further object is to provide progressive illuminating means well adapted to meet the needs of commercial service.

Further objects will appear as the description proceeds.

Figure 1 is a diagrammatic view illustrating a system embodying the principles of the present invention;

Figure 2 is a diagrammatic view illustrating a detail of construction;

Figure 3 illustrates an exciting and holding relay forming part of the system illustrated in Figure 1; and

Figure 4 illustrates another exciting and holding relay also employed in the system illustrated in Figure 1.

According to the present invention a plurality of gaseous discharge tubes may be employed such, for example, as those indicated by the numerals 11 and 12 in Figure 1. Each of said tubes is provided with a cathode 13 which may be heated from any desired source of electric current. Within each of said tubes 11 and 12 is a contact assembly indicated generally by the numeral 14. Each of the contact assemblies 14—14 includes a group of anodes indicated by the numerals 15, 16, 17 and 18 spaced along the corresponding tube. Also located in each tube is an anode 19, which may be referred to as an end anode, spaced from the anode 18. Each contact assembly 14 and the end anode 19 may be supported interiorly of its corresponding tube by any preferred means. As illustrated in Figure 2, each of the anodes 15, 16,

2

17 and 18 is carried by a support 21 and is provided with a movable electric contact 22. The anodes 15, 16 and 17 are each adapted to have electrical contact with the next succeeding anode 5 through the contact 22 thereof which is biased into engagement with the relatively fixed contact 23 which is electrically connected to the next succeeding anode. Each anode 15, 16 and 17 is connected to its corresponding electrical contact 22 through a swinging arm 24 which carries a small mass of magnetic material indicated by the numeral 25. Disposed exteriorly of the corresponding tube in proximity to each of the masses of magnetic material 25 is a magnetic coil 26 carried by a support 27. Each of the coils 26, when energized, is adapted to attract its corresponding mass of magnetic material 25 and break engagement between the corresponding contacts 22 and 23.

10 20 The system disclosed in Figure 1 employs a plurality of relays 29 and 30 which may be referred to as exciting and holding relays.

Figure 3 illustrates one of the exciting and holding relays 29 or 30. This relay is illustrated 25 as having an approximately U-shaped field structure indicated by the numeral 32 and with the pivoted armature 32'. Said armature 32' carries a contact member 33 adapted to engage the stationary contact member 34. Said armature 32' is biased as, for example, by the spring 35 to a position wherein the contact 33 engages the contact 34. Each of the relays 29 and 30 is provided with a pair of coils, one indicated by the numeral 36, being an exciting coil. The other coil, indicated by the numeral 37, is a holding coil for maintaining the relay in operated position whereby to hold the contact 33 out of engagement with the contact 34.

30 40 Other exciting and holding relays, indicated by the numerals 38 and 39, co-operate respectively with the exciting and holding relays 29 and 30.

The details of the exciting and holding relays 38 and 39 are illustrated diagrammatically in 45 Figure 4. Each of the exciting and holding relays 38 and 39 is provided with an approximately U-shaped field structure indicated by the numeral 42 and with a swinging armature 43. Said armature 43 carries a pair of electrical contacts 44 and 45 insulated from each other. Said armature 43 is biased as, for example, by a spring 46 into a position wherein the contact member 44 engages a relatively fixed contact 47 and wherein the contact 45 engages a relatively fixed 50 contact 48. When said armature 43 is in mag-

netized condition, said contact member 44 is moved into engagement with a relatively fixed contact 49 and contact member 45 is moved into engagement with member 50, which is a dead contact. The numeral 51 indicates an exciting coil adapted, when excited, to attract the armature 43. The numeral 53 indicates a holding coil for holding the armature 43 in its attracted position as long as current is passing through said holding coil.

Proceeding now to a description of the system disclosed in Figure 1, the numerals 54—54 indicate the two sides of a source of electric current controlled by the switch 54'. Connected across the lines 54—54 through the trip-switch 55 is the primary 56 of a transformer 57 having a plurality of secondaries which provide current for the full wave rectifier 58. Said rectifier 58 is adapted to deliver pulsating uni-directional current. The polarities of the rectifier 58 are indicated by the plus (+) and minus (—) signs adjacent thereto. Also connected across the lines 54—54 is the primary 59 of a transformer 60 which has the function of supplying heating current to the cathodes 13—13 of the tubes 11 and 12. Said transformer 60 also has the function of supplying current to the various relays to be referred to more in detail presently. Said transformer 60 has the secondary winding 61 adapted to supply heating current to the cathode 13 of the tube 12. Said transformer 60 also has the secondary winding 62 for supplying heating current to the cathode 13 of the tube 11.

Also connected across that part of the lines 54—54 controlled by the switch 54' is the self-starting alternating current motor 63 adapted to swing the arm 64 throughout a complete circumference engaging successively with a plurality of contact buttons indicated by the numerals 65, 66, 67, 68, 69, 70, 71, 72, 73 and 74. In the course of its travel from the button 74 back to the button 65, the arm 64 is adapted to open the trip-switch 55, which, after said arm has passed, will automatically close again. One side of the secondary 62 of the transformer 60 is connected to the swinging arm 64 and the other side of said secondary is connected to ground, that is, to a conducting member G, common to a number of electrical terminals. The button 65 is connected to one terminal of the exciting coil of the exciting and holding relay 29, the other terminal of this exciting coil being connected to ground. The contact button 66 is electrically connected to one terminal of that coil 26, which is positioned to open-circuit the anode 15 in the tube 11. The other terminal of said coil is connected to ground. In a like manner the contact button 67 is connected to that coil 26 which is adapted to open-circuit the anode 16 in tube 11, the other terminal of said coil being connected to ground. Contact button 68 in like manner is connected to a coil 26 for controlling the circuit through the anode 17, the other terminal of said coil being connected to ground. The contact button 69 is connected to one terminal of the exciting coil of the exciting and holding relay 38, the other terminal of said exciting coil being connected to ground. The contact button 70 is connected to one terminal of the exciting coil of the exciting and holding relay 30, the other terminal of said coil being connected to ground. The contact button 71 is connected to one terminal of the coil 26 positioned to open-circuit the anode 15 of the tube 12, the other terminal of said coil being con-

nected to ground. In like manner the contact buttons 72 and 73 are connected to the coils 26—26 positioned to open-circuit the anodes 16 and 17, respectively, of tube 12. The contact button 74 is connected to one terminal of the exciting coil of the exciting and holding relay 39, the other terminal of said exciting coil being connected to ground.

When the switch 54' is open and the various relays are all unexcited, a short circuit is provided across the terminals of the uni-directional power source 58 which circuit may be traced as follows: From the positive side of the uni-directional source 58 to the contact 45 of relay 39, contact 48 thereof, armature 32' of relay 30 to contact 45 of relay 38, contact 48 thereof, armature 32' of relay 29 back to the negative side of the uni-directional power source 58. In other words, the circuit just traced constitutes a bypass circuit around each of the tubes 11 and 12.

When the operator desires to start the system into operation, he will close the switch 54', energizing the uni-directional power source 58 as well as the transformer 60. The cathodes 13—13 of the tubes 11 and 12 will be heated. Moreover the motor 63 will be set into operation. Of course, the position of the swinging arm 64 will depend usually upon the position at which it was left when the switch 54' had previously been opened. For simplicity of explanation, it may be assumed that the switch arm 64 is somewhere in the space between the trip-switch 55 and the contact button 65. When said arm 64 engages the contact button 65, a circuit is completed from the secondary 62 of the transformer 60 through the arm 64, contact button 65, the exciting coil of relay 29 to ground, thence to the grounded terminal of the secondary 62. The resulting magnetization of the relay 29 will attract the armature 32', breaking circuit between the contacts 33 and 34 of said relay 29. Circuit may be traced from the positive side of the uni-directional power source 58 through contacts 45 and 48 of the exciting and holding relay 39 through the armature 32' of the relay 30 through contacts 44 and 47 of relay 38 through the holding coil 37 of relay 29 to the contact assembly 14 of tube 11, thereby charging the anodes 15, 16, 17 and 18 in said tube 11. Inasmuch as the cathode 13 has been heated, current will pass from the anode 15 of tube 11 to the cathode thereof back to the negative side of the power source 58. Inasmuch as the holding coil 37 of the relay 29 is energized, the armature 32' thereof will maintain the break in the short circuit across the uni-directional source of power 58, whereby current will continue to flow from the anode 15 to the cathode 13 of said tube, maintaining a glow therebetween.

The motor 63 in the course of its operation will move the arm 64 out of engagement with the contact button 65 and into engagement with the contact button 66, completing circuit for that coil 26 which controls the circuit of anode 15 of tube 11. When the anode 15 is open-circuited, the anode 16 is the nearest anode to the cathode 13 to be charged and current will pass between said anode 16 and the cathode 13, causing the region between these two elements to glow. In like manner, when the arm 64 engages the contact button 67, the region between the anode 17 and the cathode 13 will be caused to glow and when the arm 64 engages the contact button 68 the region between the anode 18 and the cathode 13 of tube 11 will be caused to glow.

When the arm 64 engages the contact button 69, the exciting coil 51 of the relay 38 will be energized, attracting the armature 43 thereof, moving contact 45 out of engagement with contact 48 and moving contact 44 into engagement with the contact 49. This action de-energizes the relay 29 and the contact assembly 14 in tube 11, but at the same time completes a power circuit from the positive side of the power source 58 through contacts 45 and 48 of relay 39 through armature 32' of relay 30 through contacts 44 and 49 of relay 38 through the holding coil 53 of said relay 38 to the anode 19 in tube 11. This will cause a glow throughout the length of tube 11.

As the arm 64 proceeds to the contact button 70, the relay 30 will be energized, breaking the short circuit across the tube 12, and causing current from the positive side of the uni-directional power source 58 to flow through contacts 44 and 47 of relay 39 through the holding coil of relay 30 to the contact assembly 14 of tube 12, thence from the anode 15 thereof to the cathode 13 of tube 12, thence through contacts 44 and 49 of relay 38 through the holding coil of relay 38 to anode 19 of tube 11, back through the cathode 13 to tube 11 to the negative side of the source 58. Glow will now occur between the anode 15 and cathode 13 of tube 12 as well as throughout the length of tube 11. As the contact arm proceeds to contact 74, the glow will progress through the tube 12 in a manner similar to that described in connection with tube 11.

After the arm 64 has passed the last contact button 74 it will open the switch 55 momentarily, open circuiting the primary circuit 56 of the transformer 57, thereby momentarily shutting off the power source 58. This will result in a de-energization of relays. The cycle will be re-initiated when the arm 64 again engages the contact button 65.

Though a preferred embodiment of the present invention has been described in detail, many modifications will occur to those skilled in the art. It is intended to cover all such modifications that fall within the scope of the appended claims.

What is claimed is:

1. In a progressive illuminating system, in combination, a gaseous discharge tube of the hot cathode type, a cathode and a plurality of anodes disposed inwardly of said tube, means located within said tube connecting said anodes to provide a contact assembly, each of said connecting means being provided with magnetic material and relay means disposed exteriorly of said tube adapted progressively to attract said magnetic material to open-circuit said connecting means.

2. In a progressive illuminating system, in combination, a gaseous discharge tube of the hot cathode type, a cathode and a plurality of anodes disposed inwardly of said tube, means located within said tube connecting said anodes to provide a contact assembly, each of said connecting means being provided with magnetic material and relay means disposed exteriorly of said tube adapted progressively to attract said magnetic material to open-circuit said connecting means, an end anode in said tube and relay means for controlling said end anode, said last mentioned relay means being adapted to open-circuit said contact assembly.

3. In a progressive illuminating system, in combination, a gaseous discharge tube of the hot cathode type provided with a cathode and a

plurality of anodes spaced along said tube, means located within said tube connecting said anodes to provide a contact assembly and means located exteriorly of said tube for progressively opening said connecting means.

4. In a progressive illuminating system, in combination, a gaseous discharge tube of the hot cathode type provided with a cathode and a plurality of anodes spaced along said tube, means located within said tube connecting said anodes to provide a contact assembly and means located exteriorly of said tube for progressively opening said connecting means, an end anode in said tube and relay means for controlling said end anode, said last mentioned relay means being adapted to open-circuit said contact assembly.

5. In a progressive illuminating system, in combination, a gaseous discharge tube having a cathode, a group of anodes, connecting means connecting said anodes in series and an end anode, said anodes being spaced along said tube with said end anode furthest from said cathode, a by-pass circuit for said tube, means for interrupting said by-pass circuit and directing current to said group of anodes and for progressively opening said connecting means and means for thereafter opening circuit to said group of anodes and making circuit to said end anode.

6. In a progressive illuminating system, in combination, a gaseous discharge tube of the hot cathode type provided with a cathode and a plurality of anodes spaced along said tube, means located within said tube separably connecting said anodes to one another, conducting means for delivering current to said anodes and connecting means located exteriorly of said tube and means for progressively open-circuiting said connecting means.

7. In a progressive illuminating system, in combination, a gaseous discharge tube of the hot cathode type provided with a cathode and a plurality of anodes spaced along said tube, means located within said tube separably connecting said anodes to one another, conducting means for delivering current to said anodes and connecting means located exteriorly of said tube and means for progressively open-circuiting said connecting means, another anode in said tube and means for connecting said other anode in circuit when said conducting means is open-circuited.

8. In combination, a gaseous discharge tube having a cathode and anodes spaced along said tube, means connecting said anodes to one another to provide a contact assembly, means for delivering current to said assembly, an end anode in said tube, a by-pass circuit for said tube, a plurality of relay means for open-circuiting said by-pass circuit and directing current to said connecting means to cause discharge from said anodes, means for energizing said relay means in progression and means for closing circuit to said end anode when all of said connecting means have been open-circuited.

9. In combination, a gaseous discharge tube having a cathode and a plurality of anodes spaced along said tube, separable contacts connecting said anodes into a contact assembly, means for delivering current to said assembly, magnetic means located exteriorly of said tube for controlling said contacts and means for progressively energizing said magnetic means to progressively control said anodes.

10. In combination, a gaseous discharge tube having a cathode and a plurality of anodes

spaced along said tube, separable contacts connecting said anodes into a contact assembly, means for delivering current to said assembly, magnetic means located exteriorly of said tube for controlling said contacts and means for progressively energizing said magnetic means to progressively control said anodes, an end anode and means for charging said end anode when said anodes in said contact assembly are open-circuited.

11. In combination, a gaseous discharge tube having a cathode and a plurality of anodes spaced along said tube, separable contacts connecting said anodes, means for delivering current to said anodes and said contacts, an end anode in said tube, magnetic means for controlling said contacts, a by-pass circuit for said tube and progressively operable means for open-circuiting said by-pass circuit and directing current to said anodes, maintaining said by-pass circuit in open-circuit condition while current is flowing in said tube and opening said contacts in succession.

12. In combination, a gaseous discharge tube having a cathode and a plurality of anodes spaced along said tube, contact means connecting said anodes, conducting means for delivering current to said anodes and said contact means, magnetic means disposed exteriorly of said tube for controlling said contact means, a by-pass circuit for said tube, means for progressively energizing said magnetic means, said magnetic means being adapted to open said by-pass circuit and direct current to said contact means and progressively open said contact means.

13. In combination, a gaseous discharge tube having a cathode and a plurality of anodes spaced along said tube, contact means connecting said anodes, conducting means for delivering current to said anodes and said contact means, magnetic means disposed exteriorly of said tube for controlling said contact means, a by-pass circuit for said tube, means for progressively energizing said magnetic means, said magnetic means being adapted to open said by-pass circuit, direct current to said contact means and progressively open said contact means, an end anode in said tube, said magnetic means being adapted to connect said end anode in circuit when the anode next adjacent thereto is disconnected.

14. In combination, a gaseous discharge tube having a cathode and a plurality of anodes spaced along said tube, contact means connecting said anodes, magnetic means disposed exteriorly of said tube for controlling said contact means, a by-pass circuit for said tube, means for progressively energizing said magnetic means for breaking circuit through said by-pass circuit, direct current to said contact means and progressively open said contact means, and for maintaining said short-circuiting means in broken circuit condition as long as current is passing from one of said anodes to said cathode.

15. In a progressive illuminating system, in combination, a gaseous discharge tube having a cathode and a plurality of anodes spaced therewith, contacts adapted to connect said anodes to provide a contact assembly, conducting means for delivering current to said contact assembly, means for progressively controlling said contacts to progressively vary the length of glow of said

tube, an end anode of said tube and relay means for open-circuiting said connecting means and closing circuit to said end anode.

16. In a progressive illuminating system, in combination, a plurality of gaseous discharge tubes, each having a cathode and a plurality of anodes spaced therewith, said anodes being connected together by contact members into a contact assembly, a by-pass circuit for each of said tubes, an end anode in each of said tubes, progressively operable magnetic means for open-circuiting each of said by-pass circuits and for directing current to said contact assembly of the corresponding tube and for maintaining said by-pass circuit in such current directing relationship while current is flowing in its corresponding tube, for open-circuiting said contact members, for connecting in circuit the end anode in each tube, and for connecting the end anode of one tube with the cathode in the next succeeding tube.

17. In a progressive illuminating system, in combination, a plurality of gaseous discharge tubes, each having a cathode, a group of anodes, connecting means connecting said anodes in series and an end anode, by-pass circuit means for said tubes, relay means for opening said by-pass circuit means and for directing current to said connecting means and for progressively open circuiting said connecting means to cause progressive discharge from said anodes in said group in one of said tubes, relay means for controlling discharge from the end anode in said first tube, other relay means for progressively controlling discharge from said anodes progressively in the other of said tubes and means responsive to said relay means for connecting the cathode of one tube to the end anode of the preceding tube.

18. In a progressive illuminating system, in combination, a plurality of gaseous discharge tubes, each provided with a cathode and a plurality of anodes spaced therewith, means connecting said anodes in each tube to one another to provide a contact assembly, means for delivering current to said contact assembly, relay means for open-circuiting said current delivery means, an end anode in each of said tubes, means for controlling said connecting means, by-pass circuit means for said tubes, means operative for each of said tubes in succession for open-circuiting said by-pass circuit means and directing current to the contact assembly of the corresponding tube, for progressively opening said connecting means in said contact assembly and for connecting said end anode in circuit for controlling the discharge from said anodes in progression and relay means for connecting the cathode in one of said tubes to the end anode of the next preceding tube.
